[57] CLAIM

The ornamental design for tray bracket holder for a telephone handset or similar article, as shown and described.

DESCRIPTION

FIG. 1 is a front, and right side perspective view of a tray bracket holder for a telephone handset or similar article;

FIG. 2 is a front elevational view thereof;

FIG. 3 is a top plan view thereof;

FIG. 4 is a rear elevational view thereof;

FIG. 5 is a bottom plan view thereof;

FIGS. 6 and 7 are respectively right and left side elevational view thereof.

The broken line showing of a telephone handset and an electric line in FIGS. 1 and 2 is for illustrative purposes only and forms no part of the claimed design.

FIG. 1

FIG. 2

FIG. 3

FIG. 4

FIG. 5

FIG. 6

FIG. 7
